EVELYN L. V. HOWELL, OF LOS ANGELES, CALIFORNIA, ASSIGNOR OF ONE-HALF TO
HERMAN M. SCHROEDTER, OF LOS ANGELES, CALIFORNIA.

SHOCKLESS RAIL-CROSSING.

1,396,686.

Specification of Letters Patent. Patented Nov. 8, 1921.

Application filed June 20, 1921. Serial No. 478,836.

To all whom it may concern:

Be it known that I, EVELYN L. V. HOWELL, citizen of the United States, residing in Los Angeles, county of Los Angeles, State of California, have invented new and useful Improvements in Shockless Rail-Crossings, of which the following is a specification.

This invention has to do with a shockless rail intersection or crossing and it is an object of the invention to provide a simple, effective improved structure of this character.

A particular object of the invention is to provide a simple yet positive shockless rail crossing. In carrying out this object a structure has been provided which is positive and reliable in operation and is simple, durable and inexpensive of construction.

A noteworthy feature of the invention is the provision of a simple structure of the character specified which will be positively operated by a car or the like approaching the crossing from either direction on either track.

The various objects and features of the invention will be best and more fully understood from the following detailed description of a typical embodiment of the invention throughout which reference is had to the accompanying drawings in which—

Figure 1 is a plan view of a typical track intersection embodying the present invention, the cover plate being removed for the purpose of showing the mechanism provided by the invention; Fig. 2 is a vertical detail sectional view taken as indicated by line 2—2 on Fig. 1; Fig. 3 is a view similar to Fig. 2 showing the mechanism in another position; Fig. 4 is a vertical detail sectional view taken as indicated by line 4—4 on Fig. 2; Fig. 5 is a vertical detail sectional view taken as indicated by line 5—5 on Fig. 2; Fig. 6 is an enlarged plan view of a portion of the structure shown in Fig. 5 being a view taken as indicated by line 6—6 on Fig. 5 and Fig. 7 is an enlarged view of a portion of the structure shown in Fig. 5.

Throughout the drawings letters T and T' designate intersecting tracks each of which comprises two parallel rails 10. For the purpose of disclosing the invention in its simplest form I am illustrating it as applied to an intersection at which the two tracks cross at right angles with each other it being understood, however, that the invention may

be applied to intersections wherein the tracks cross at various angles. In accordance with the present invention each rail is formed with a space where it is intersected by another rail. These spaces are to accommodate wheel flanges and will be hereinafter termed flange spaces. As each rail 10 is intersected by two other rails there are two flange spaces in each rail and there are two flange spaces at each rail intersection, one in each of the intersecting rails. For each flange space there is a movable member A comprising an arm 20, a plug 13 at the end of the arm, an extension 14, a neck 15 connecting the plug and extension, and a toothed segment 16 at the end of the extension. The arms 20 are pivotally connected to the sides of the rails by pivot pins 12 at points spaced considerably outward of the rail intersections. The arms extend inwardly from the pivot pins so that the plugs, which are at their ends, are at the flange spaces. The arms being pivotally connected to the rails are movable to an up position where the plugs fill the flange spaces and form continuations of the rails and are movable downwardly to a down position where the plugs do not restrict the flange spaces. When the arms are up so that the plugs fill the flange spaces their upper surfaces 19 are inclined to extend inwardly and upwardly from the pivot pins to the upper parts of the plugs so that the flanges of wheel passing over the rails toward the intersections will engage them. Engagement of the arms by the wheel flanges will force or push them downwardly until they are in the down position. When the arms are in the down position their upper surfaces are substantially horizontal. When the arms or movable members, in connection with the rails of one track are up the flange spaces in the rails of the other track are filled so that wheels can pass over them without shock or jar.

The movable members in connection with each rail are positively connected together so that operation of one will cause operation of the other and so that they are always in the same operative positions. The movable members of each rail are directly connected by the meshing of the toothed segments 16 at the ends of the extensions 14. The manner in which the segments of the movable members mesh or coöperate to directly connect the two movable members of

each rail is clearly illustrated in the drawings. The necks 15 of the movable members at each rail intersection are shaped and proportioned so that the members can be moved up and down in the manner above described without interfering with each other. The extensions 14 are connected to the plugs 13 by the necks 15, so that their upper surfaces 18 are in line with the upper surfaces 19 of the arms 20.

The two movable members at each rail intersection are connected together so that one is up when the other is down, and so that when one is moved or operated the other is moved or operated in the opposite direction. The connection between the two members comprises two racks 30, one in connection with each of the members, and a pinion 31 engaged by the racks. The racks 30 are connected to the members by pins 34 carried in slots 35 in the members, and face each other so that they engage opposite sides of the pinion. The racks 30 of the two members are relatively positioned in engagement with the pinion so that the two members are in opposite positions, that is, so that one of the members is up while the other is down. Movement of one of the members will, through the racks and pinion, cause opposite movement of the other member. The racks 30 can, of course, be guided in any suitable manner to cause them to properly engage and coöperate with the pinion. For instance they can be provided with extensions 38 adapted to be slidably carried by suitable stationary guides 39. The pinions 31 are carried on shafts 40 supported by suitable bearings 41. Each of the shafts 40 carries two pinions 31 and therefore further interconnect the various parts of the mechanism.

A pit B is provided at the crossing to carry various parts of the mechanism in the manner clearly illustrated in the drawings and suitable supports 60 are arranged in the pit to carry a cover plate (not shown) for the pit.

In operation when the mechanism is in the position shown in Figs. 1, 2, 4, 5, 6 and 7 of the drawings wheels can pass over the track T in either direction without shock. The flanges of wheels passing over track T' in either direction will engage an arm 20 in connection with each rail of track T' as the wheels approach the crossing. The flanges force or push the arms that they engage downwardly causing movement of all of the members A in connection with the rails of track T' to the down position due to the interconnections above described. When the members A in connection with track T' are down the flange spaces in the rails of track T are unrestricted. The movement of the members A in connection with track T' to the down position causes move-

ment of the members A in connection with track T to the up position because of the interconnections above described. When the members A in connection with track T are up the flange spaces in track T' are filled so the wheels can pass over track T' without shock or jar. When the mechanism has been operated in the manner just described it is positively held in the operated position as long as there is a wheel at the crossing on track T'. The wheels at the crossing positively hold the mechanism by engaging and holding down the arms 20 and extensions 14 of the members in connection with the rails of the track on which the wheels are carried. Fig. 3 of the drawings shows the manner in which the mechanism is operated by a wheel flange to fill the flange spaces over which the wheel is to pass before it reaches them. It will be understood of course that the arms may be made comparatively long so that the operation of the mechanism will be comparatively slow and to assure complete operation before the wheels reach the flange spaces. It will be obvious how the mechanism will be operated back to the position shown in Figs. 1, 2, 4, 5, 6 and 7, of the drawings by wheels on track T.

From the foregoing description it will be understood how the present invention provides a particularly simple, durable, reliable mechanism. The interconnection of the various parts of the mechanism through the toothed segments 16, the racks and pinions, and the shafts 40 positively assures complete operation of every part of the mechanism and thus makes the mechanism effective and reliable. A particular feature of the invention is the simple compact inexpensive manner in which the various parts are interconnected.

Having described only a preferred form of my invention I do not wish to limit myself to the particular details hereinabove set forth but wish to reserve to myself any changes or modifications that may appear to those skilled in the art and that may fall within the scope of the following claims.

Having described a preferred form of my invention, I claim:

1. In combination with two intersecting rails having flange spaces at the intersection, a movable member in connection with each rail comprising, an arm having an up position where it will be engaged by the flange of a wheel passing over the rail toward the intersection and adapted to be moved to a down position by the flange, and a plug carried by the arm to fill the flange space in the other rail when the arm is up and to leave said flange space unrestricted when the arm is down, and means connecting the two members in opposite positions and so that they operate each other.

2. In combination with two intersecting rails having flange spaces at the intersection, a movable member in connection with each rail comprising, an arm having an up position where it will be engaged by the flange of a wheel passing over the rail toward the intersection and adapted to be moved to a down position by the flange, and a plug carried by the arm to fill the flange space in the other rail when the arm is up and to leave said flange space unrestricted when the arm is down, and mechanical means connecting the two members in opposite positions and so that they operate each other.
- 15 3. In combination with two intersecting rails having flange spaces at the intersection, a movable member in connection with each rail comprising, an arm having an up position where it will be engaged by the flange of a wheel passing over the rail toward the intersection and adapted to be moved to a down position by the flange, and a plug carried by the arm to fill the flange space in the other rail when the arm is up and to leave said flange space unrestricted when the arm is down, and rack and pinion mechanism connecting the two members in opposite positions and so that they operate each other.
- 20 4. In combination with two intersecting rails having flange spaces at the intersection, a movable member in connection with each rail comprising, an arm having an up position where it will be engaged by the flange of a wheel passing over the rail toward the intersection and adapted to be moved to a down position by the flange, and a plug carried by the arm to fill the flange space in the other rail when the arm is up and to leave said flange space unrestricted when the arm is down, and rack and pinion mechanism connecting the two members in opposite positions and so that they operate each other.
- 25 5. In combination with two intersecting rails having flange spaces at the intersection, a movable member in connection with each rail comprising, an arm pivotally connected to the rail at a point substantially removed from the intersection and arranged to extend toward the intersection, the arm having an up position where it will be engaged by the flange of a wheel passing over the rail toward the intersection to be moved to a down position by the flange, and a plug carried by the arm to fill the flange space in the other rail when the arm is up and to leave said flange space unrestricted when the arm is down, and rack and pinion mechanism connecting the two members in opposite positions and so that they operate each other.
- 30 6. In combination with two intersecting tracks each comprising two parallel rails with a flange space at each rail intersection, a movable member in connection with each rail at each rail intersection comprising an arm having an up position where it will be engaged by the flange of a wheel passing over the rail toward the intersection and adapted to be moved by the flange to a down position, and a plug carried by the arm to fill the flange space in an intersecting rail when the arm is up and to leave said flange space unrestricted when the arm is down, and means connecting the two movable members of each rail so that they operate together.
- 35 7. In combination with two intersecting tracks each comprising two parallel rails with a flange space at each rail intersection, a movable member in connection with each rail at each rail intersection comprising an arm having an up position where it will be engaged by the flange of a wheel passing over the rail toward the intersection and adapted to be moved by the flange to a down position, and a plug carried by the arm to fill the flange space in an intersecting rail when the arm is up and to leave said flange space unrestricted when the arm is down, and means directly connecting the two movable members of each rail so that they operate together.
- 40 8. In combination with two intersecting tracks each comprising two parallel rails with a flange space at each rail intersection, a movable member in connection with each rail at each rail intersection comprising an arm having an up position where it will be engaged by the flange of a wheel passing over the rail toward the intersection and adapted to be moved by the flange to a down position, and a plug carried by the arm to fill the flange space in an intersecting rail when the arm is up and to leave said flange space unrestricted when the arm is down, and a toothed segment at the inner end of the movable member, the toothed segments of the two movable members of each rail co-operating so that said movable members are directly connected to operate together.
- 45 9. In combination with two intersecting tracks each comprising two parallel rails with a flange space at each rail intersection, a movable member in connection with each rail at each rail intersection comprising an arm having an up position where it will be engaged by the flange of a wheel passing over the rail toward the intersection and adapted to be moved by the flange to a down position, and a plug carried by the arm to fill the flange space in an intersecting rail when the arm is up and to leave said flange space unrestricted when the arm is down, means

connecting the two movable members of each rail so that they operate together, and means connecting the two movable members at each rail intersection so that they operate oppositely.

10. In combination with two intersecting tracks each comprising two parallel rails with a flange space at each rail intersection, a movable member in connection with each rail at each rail intersection comprising an arm having an up position where it will be engaged by the flange of a wheel passing over the rail toward the intersection and adapted to be moved by the flange to a down position, a plug carried by the arm to fill the flange space in an intersecting rail when the arm is up and to leave said flange space unrestricted when the arm is down, means positively connecting the two movable members of each rail so that they operate together, and means positively connecting the two movable members at each rail intersection so that they operate oppositely.

11. In combination with two intersecting tracks each comprising two parallel rails with a flange space at each rail intersection, a movable member in connection with each rail at each rail intersection comprising an arm having an up position where it will be engaged by the flange of a wheel passing over the rail toward the intersection and adapted to be moved by the flange to a down position, a plug carried by the arm to fill the flange space in an intersecting rail when the arm is up and to leave said flange space unrestricted when the arm is down, and means interconnecting the movable members so that the arms of those in connection with one track are up while the arms of those in connection with the other track are down.

12. In combination with two rails having flange spaces, a movable member in connection with each rail comprising, an arm having an up position where it will be engaged by the flange of a wheel passing over the rail and adapted to be moved to a down position by the flange, and a plug carried by the arm to fill a flange space when the arm is up and to leave said flange space unrestricted when the arm is down, and a rack and pinion mechanism connecting the two members so that they operate each other.

13. In combination with two intersecting tracks each comprising two parallel rails with a flange space at each rail intersection, a movable member in connection with each rail at each rail intersection comprising an arm having an up position where it will be engaged by the flange of a wheel passing over the rail toward the intersection and adapted to be moved by the flange to a down position, and a plug carried by the arm to fill the flange space in an intersecting rail when the arm is up and to leave said flange

space unrestricted when the arm is down, 65 the two movable members in connection with each rail being adapted to be moved by the flanges of wheels passing over the rail in opposite directions, and means connecting the two movable members of each rail so that 70 they operate together.

14. In combination with two intersecting tracks each comprising two parallel rails with a flange space at each rail intersection, a movable member in connection with each 75 rail at each rail intersection comprising an arm having an up position where it will be engaged by the flange of a wheel passing over the rail toward the intersection and adapted to be moved by the flange to a down 80 position, a plug carried by the arm to fill the flange space in an intersecting rail when the arm is up and to leave said flange space unrestricted when the arm is down, and a toothed segment at the inner end of the 85 movable member, the toothed segments of the two movable members of each rail co-operating so that said movable members are directly connected to operate together, the movable members in connection with each 90 rail being oppositely disposed so that one of them is engaged by the flanges of wheels approaching the intersection in one direction while the other is engaged by the flanges of wheels approaching the intersection in the 95 other direction.

15. In combination with two intersecting tracks each comprising two parallel rails with a flange space at each rail intersection, a movable member in connection with each 100 rail at each rail intersection comprising, an arm having an up position where it will be engaged by the flange of a wheel passing over the rail toward the intersection and adapted to be moved by the flange to a down 105 position, a plug carried by the arm to fill the flange space in an intersecting rail when the arm is up and to leave said flange space unrestricted when the arm is down, and a toothed segment at the end of the member, the toothed segments of the two members of each rail co-operating so that said movable members are directly connected to operate together and one from the other, a pinion at each rail intersection, the pinions having 110 fixed axes of rotation, a rack connected to each movable member, the racks at each rail intersection being arranged in engagement with opposite sides of the pinion with the movable members of that intersection in 115 opposite positions, and means for guiding the racks to co-operate with the pinions.

In witness that I claim the foregoing I have hereunto subscribed my name this 14th day of June, 1921.

EVELYN L. V. HOWELL.
Witness:
VIRGINIA BERRINGER.
